UNITED STATES PATENT OFFICE.

CHARLES B. CAMPBELL AND WILLIAM H. CAMPBELL, OF BUFFALO, N. Y.

MACHINE FOR GROOVING METAL ROLLS.

SPECIFICATION forming part of Letters Patent No. 331,613, dated December 1, 1885.

Application filed August 29, 1885. Serial No. 175,637. (No model.)

To all whom it may concern:

Be it known that we, CHARLES B. CAMPBELL and WILLIAM H. CAMPBELL, of Buffalo, in the county of Erie and State of New York, have invented a new and useful Improvement 5 in Machines for Grooving Metal Rolls, which improvement is fully set forth in the following specification, and shown in the accompanying drawings.

10 The object of our invention is to produce a power machine or engine for automatically grooving or corrugating the surfaces of chilled rolls used in flour-milling or for other similar work, means being provided for making the 15 grooves of different depths and grades of fineness, and for varying the wind or twist of the same, or for making them straight, the parts and devices entering into the construction of the engine being fully described in the following 20 specification, and more particularly pointed out in the claims.

The process of corrugating chilled rolls for flour-milling with the devices heretofore used has been slow and expensive, and in our present 25 invention we aim to materially shorten the time and reduce the expense of this operation by increasing the number and changing the form of the grooving-tools used, besides making the engine automatic in its operations, so that the least amount of time is lost 30 in shifting the work and adjusting the cutters.

Referring to the drawings, Figure 1, Sheet 1, is a general view of our improved power corrugating-engine, being a front elevation of the same, with a part of the hydraulic cylinder, plunger, worm-gear, and other parts vertically and centrally sectioned, to better show the construction of the same, parts being broken away, and other parts not essential to 40 the figure wholly omitted. Fig. 2, Sheet 2, is a side elevation of the engine, viewed as indicated by arrow x in Fig. 1, drawn to further show the devices for operating the escape-valves for the cylinder, the devices for turning the roll on its axis while being corrugated, the means to raise and lower the guide, and other parts of the engine, parts being broken away and other parts omitted. Fig. 3, Sheet 45 3, is a rear elevation of the engine, viewed from a direction opposite to that from which Fig. 1 is seen, drawn to further and more fully

show the means for turning the roll to give the corrugations a spiral form, and the means for operating the escape-valves of the hydraulic cylinder, parts being shown in two 55 positions by full and dotted lines, and other parts of the machine wholly omitted. Fig. 4, Sheet 4, is a plan of a portion of the cross-head for holding the tools, drawn to a larger scale, to show more fully the radial tool-holder, 60 the manner in which the grooving-tools surround the body to be corrugated, and the manner of adjusting the tools to the work and withdrawing them from the same during retrograde movements of the machine, parts being 65 broken away and omitted, and one of the posts and a stem of the roll transversely sectioned, as on the dotted line y in Fig. 1, the whole being viewed as indicated by arrow z in said figure. Fig. 5, Sheet 5, drawn to an 70 enlarged scale, is an elevation of a portion of the right-hand post of the engine and other parts at the right of the center line thereof, viewed in the same direction in which Fig. 1 is seen, drawn to show the manner of forcing 75 water into the cylinder and regulating the operation of the pumps, and to show more fully the devices for withdrawing the grooving-tools from the work and operating the discharge-valves for the cylinder, parts being 80 broken away and omitted, and other parts shown as occupying two positions by full and dotted lines. Fig. 6, Sheet 6, is a plan of the extended flange of the cylinder, forming a bed-plate for the engine, and other 85 parts, viewed in a direction indicated by arrow x' in Fig. 3, the posts being transversely sectioned, as on the dotted line y' therein, drawn to further show the bowed girt or rest for the inclined slide, and other parts of the 90 devices for giving the corrugations a spiral form and indexing the roll, parts not essential to the figure being omitted. Fig. 7 is a plan of the worm-gear, viewed from the same direction from which Fig. 6 is seen, drawn to a 95 much larger scale, for the purpose of better showing the clamp for the roller-stem or work-opposing adjusting-screws, and other parts connected therewith, the said stem and vertical thrust-bolts being horizontally sectioned, as on 100 the dotted line y'' in Fig. 3, parts being shown in two positions of adjustment by full and

dotted lines. Fig. 8, Sheet 7, is a view of the lower part of the hydraulic cylinder and parts immediately connected therewith, viewed from the same direction from which Fig. 1 is seen, 5 the cylinder being in part vertically sectioned, as on the broken dotted line x^2 in Fig. 9, one of the exhaust-tubes and parts joining the same being vertically and centrally sectioned on the same line, to better show the construction thereof. Fig. 9 is a transverse section of the cylinder and some other parts, taken as on the dotted line z' in Fig. 8, and viewed as indicated by the arrow z^2 therein, drawn to more clearly show the arrangement of the exhaust-tubes, one of the latter being transversely sectioned, as on the dotted line x^3 in Fig. 8. Fig. 10 is a view of a part of the apparatus for operating the escape-valves of the cylinder, viewed from the direction from which Fig. 2 is seen, drawn to a larger scale, to show more clearly the parts therein represented, parts being shown in two positions by full and dotted lines. Fig. 11 is a view of some of the parts shown in Fig. 10, drawn in different relative positions, to more clearly show the operation of the same. Fig. 12 is a plan of the parts shown in Fig. 10, the cylinder, with its stiffening-brace, being horizontally sectioned, as on the dotted line z^3 in Fig. 10, and viewed 25 as indicated by the arrow therein, drawn to further and more fully show the parts and their arrangement. Fig. 13, Sheet 1, is an elevation of a part at the lower end of the guide for the work, viewed in the direction in which Fig. 1 is seen, drawn to a larger scale, to better show the construction of the parts, the contracting-nut being broken away in part to uncover a slit in the guide. Fig. 14 is a view at the end of the same, seen as indicated 30 by arrow in Fig. 13, the upper roller-stem being transversely sectioned, as on the dotted line y^3 in said figure, the yielding parts or jaws at the end of the guide-bar being shown in different positions by full and dotted lines. Fig. 15, Sheet 4, is a side elevation of the segment arm or rocker for withdrawing the cutters from the work, viewed as indicated by arrow x^4 in Fig. 4, said arm being shown in its positions at either end of its throw by full 35 and dotted lines. Fig. 16 is a plan of the radial tool-holder shown in part in Fig. 4, drawn to a smaller scale, to show the relation between the radial cutters or corrugating-tools and the body being operated upon, a part 40 of the cap-plate being broken away to uncover parts beneath. Fig. 17 is a view from the same direction of the tool-rest and the cross brace or lintel at the top of the posts, drawn to show the relative positions of said parts, with 45 the guide-bar, rack, and pinion, and other parts. Fig. 18, Sheet 8, shows, drawn to a much larger scale, a tool-stock and cutter, with the means for delicately adjusting the latter to its work, parts being horizontally and centrally sectioned, as on the dotted line y^4 in Fig. 20, showing better the form of the cutter and its relation to the roll. Fig. 19 is a side ele-

vation of the same, with the cap-plate, slotted ring, and other parts added, viewed as indicated by arrow z^4 in Fig. 18, the tool-stock and other contiguous parts being vertically sectioned, as on the dotted line x^5 in Fig. 20, the tool-stock, with its tool or cutter and adjusting devices, being shown in two positions of horizontal adjustment by full and dotted lines; Fig. 20, an elevation of the part shown in Fig. 19, viewed as indicated by arrow y^5 in said latter figure, a part of the slotted ring being broken away to uncover the friction-bushing of the adjusting-stud for the tool. Fig. 21 is a view of a portion of the cross-head, with the slotted ring, tool-stock, gib-slide, and other contiguous parts, viewed in the direction indicated by arrow z^5 in Fig. 4, Sheet 4, parts being vertically sectioned, as on the dotted line x^6 therein, drawn to show more fully the form of the gib-slide and its fastenings and the parts connected therewith. Fig. 22 is a view from overhead of a portion of the flange of the cylinder or bed-plate of the engine, with the shafts and other parts for pumping mounted thereon, a post being shown transversely sectioned, as on the dotted line y^6 in Fig. 5, Sheet 5. Fig. 23 is a view at the end of one of the tool-stocks, with the cutting-tool secured in place, viewed as indicated by arrow z^6 in Fig. 19, showing the form of the grooving-teeth of said cutter. Fig. 24 is a view of the face of a cutter turned against or contiguous to the tool-stock, drawn to show more fully the circular groove and transverse tongue thereof; and Fig. 25, a view of a portion of one end of a tool-stock, seen as indicated by arrow x^7 in Fig. 19, showing the seat for the cutter and the corresponding circular tongue and transverse groove made to fit the groove and tongue of the cutter just mentioned; Fig. 26, Sheet 2, a side elevation of the indexing-wheel and combined parts, drawn to a larger scale, showing the manner in which the parts are operated by the lever coming in contact with the pin of the indexing-rod, as said parts are carried upward by the plunger, parts being shown in two positions by full and dotted lines; Fig. 27, a similar view of some of the same parts, showing in dotted lines the indexing-wheel as having been carried farther upward by the plunger, resulting in the bending downward of the jointed lever against the action of the lifting-spring; Fig. 28, a view of some of the parts shown in Fig. 26, viewed as indicated by arrow y^7 in said latter figure, drawn to further show the jointed lever and spring operating the same; Fig. 29, a view of the jointed lever, pawl, and ratchet shown in Fig. 26, viewed from the opposite direction from which said latter figure is seen, drawn to more fully show the stop-screw that serves to regulate the throw of the pawl as it acts upon the teeth of the ratchet; Fig. 30, Sheet 9, an elevation of some of the devices for shifting the clutch for driving the force-pumps, viewed in the direction indicated by arrow z^7 on Sheet 5, drawn to a larger scale, to show the bell-crank of the

shifting device and its relation with the V-headed spring-bolt and other parts of the clutch-shifter; Fig. 31, a view of some of the parts shown in Fig. 30, viewed in the direction indicated by arrow x^s in said latter figure, serving to further show the relation between the V's of the bell-crank and spring-bolt, the former being transversely sectioned, as on the dotted line y^s in said Fig. 30, and the foot 5 of the shifting-fork being centrally sectioned at one end, as upon the dotted line x^s in Fig. 30, to show the slot therein. Fig. 32 shows the V-heads of the bell-crank and spring-bolt in a position which they assume at each movement of the former, viewed as Fig. 31 is seen; Fig. 33, a view of the parts of the clutch-shifting device shown in Fig. 31, and viewed in the same direction, the V-heads being in a different relative position, with the clutches 10 thereof apart; Fig. 34, a plan of the parts shown in Fig. 30, viewed as indicated by the arrow y^o , drawn to further show the relation of some of the parts, the long arm of the bell-crank being shown as reaching to a point 15 near the plunger. Fig. 35, Sheet 4, is a section of the slotted ring and tool-holder, taken upon the dotted line z^o in Fig. 4, and viewed as indicated by the arrow, drawn to better show the relation of said parts; Fig. 36, Sheet 20 30, 3, a view, drawn to a larger scale, of the head of one of the thrust-bolts and parts associated therewith shown in the adjacent figure, for urging the roll upward, the cap of the bolt being vertically and centrally sectioned, to 35 better show its form; Fig. 37, Sheet 1, a view of the roll with its stems driven into place, the roll being in part centrally and longitudinally sectioned, to show the parts of the stems fitted therein; and Fig. 38, Sheet 4, a modification of the manner of connecting the screw-shaft and slotted ring.

In preparing flour-milling rolls they are first cast with chilled surfaces, then bored longitudinally and centrally at the ends to receive steel stems H, as shown in Fig. 37, Sheet 45 1, which stems are closely fitted and permanently driven to their places in the rolls under a powerful press. The whole is then truly turned in a lathe, and in the subsequent process of corrugation the stems are grasped by suitable holders, firmly holding the roll in a vertical position, as clearly shown in Fig. 1.

Referring to the parts, A³ is a cylinder-piece or "cylinder" formed with a cylinder proper, 50 C, and a broad rectangular flange, A, at the upper end thereof, having four stout braces, G, which extend to said flange for strengthening it, and are arranged longitudinally ninety degrees apart around the cylinder C, said cylinder C, flange, and braces being all cast in one piece, and together constituting the cylinder-piece A³.

B are four supports for the cylinder, one placed at each corner of the flange and resting 55 upon solid foundations F, of masonry, about level with the floor, part of the cylinder pending in the pit D, between the foundation-

walls, as shown in Fig. 1. The plan of the flange of the cylinder is at right angles with the axis of the bore, said bore opening out at the surface of the flange, and when resting upon the supports B the axis of the cylinder is vertical.

I are two similar and equal vertical posts or supports based, respectively, at the middle 70 of the ends of the flange of the cylinder, to which they are firmly bolted.

K is a cross brace or lintel secured rigidly at the upper ends of the posts, which, together with the posts and cylinder, forms a 80 rigid frame for supporting other parts of the engine.

L is a horizontal cross-head or tool-frame reaching across between the posts, formed with broad bearing-surfaces P at its ends, 85 fitted to the parallel parts N of the posts, to be adjusted vertically along the same.

O is a vertical guide-shaft for the work as it moves upward or downward, fitted to slide through the bore of the central hub, R, 90 of the lintel as a guide, the lower end of which shaft is bored out for the purpose of receiving and holding within it the upper stem of the roll or body to be corrugated.

S is a plunger closely fitted to the bore of 95 the cylinder-piece, projecting out at the open end or mouth of the same, and provided with a lateral flange or head, T, at its upper projecting end, overlapping the flange of the cylinder.

A' is a worm-gear of the indexing device C³, resting, by means of a shoulder or bearing, a, upon the head T of the plunger, said gear being formed with a sleeve or long hub, B', reaching down into a cavity, b, formed in the 100 plunger, the said gear and the sleeve being fitted to turn as with a journal-bearing upon and within the plunger.

The worm-gear is formed with a cavity, c, extending centrally through the hub or sleeve, 110 within which is fitted a concentric ring, d, which receives within its bore the lower stem of the roll, as shown. The bores of the cylinder, plunger, worm-gear, and ring d are all concentric and nicely fitted together, the axes 115 of all coinciding with the axis of the roll and its stems and the axis of the shaft O, and when water is forced into the cylinder below the plunger, by means hereinafter set forth, the latter, with the parts above it, is carried 120 upward truly along said axial line, the same being the axial line of the engine.

The cross-head L is formed with a large central cavity, T², concentric with the axis of the engine, and supports an annular tool-holder, A², formed with equally-spaced races or rests p², in which to receive tools B³.

Referring more particularly to Sheet 8, C' are steel prismatic bodies or stocks, to which the grooving-cutters f are secured, said stocks 130 being rectangular in cross-section, so as not to turn in their bearings or seats. The steel cutters f are let into the lower faces of the respective stocks at the inner ends thereof,

and held in place by one or more bolts, *g*. Circular grooves *e*, formed in the sides of the cutters, Fig. 24, and fitted by corresponding tongues, *i*, of the stocks, Fig. 25, serve to hold 5 said cutters more firmly and truly in their seats upon their respective stocks. Tongues *n*, also projecting from the faces of the cutters into corresponding grooves, *o*, formed in the stocks, serve the same purpose. These stocks 10 are truly planed or finished upon their four respective faces to a uniform size, and fitted in radial tool races or seats *p*², formed in the annular tool-holder *A*². (Better shown on Sheet 4, Figs. 4 and 16.) By this means the cutters are held to encircle the roll, being equally 15 spaced therearound, with the scalloped cutting edges or noses of the cutters presented to the chilled surface of the same. When the roll is carried slowly upward by the rising plunger, as above stated, it is forced through this circle of cutters, and longitudinal grooves are formed in its convex surface. The roll is carried by the action of the plunger to some distance above the cutters, as indicated by dotted 20 25 position on Sheet 5, when the flow of water into the cylinder is stopped and outflow or exhaust valves, hereinafter described, opened to allow the water to escape, to permit the plunger, with the roll and other parts, to descend by gravity to the points from which they started. The roll and index *C*³ are connected, so that if the latter be turned the roll 30 35 will move also, on account of which the latter may be set for a new cut at each return movement of the plunger.

In Fig. 7, Sheet 6, *k* is a simple clamp split out at one side, at *l*, and bored to receive a stem of the roll, when the latter is put in place in the engine. A clamp-bolt, *p*, crossing 40 the slit at right angles, serves to draw the divided parts together and cause the clamp to firmly pinch the stem of the roll. Horizontal adjusting-screws *t*, threaded within rigid studs *w*, rising from the worm-gear, have their 45 respective points bearing against extended parts *v* of the clamp. By means of the clamp the cylinder and worm-gear are held to turn together, and on account of the adjusting-screws the roll may at pleasure be turned 50 to a limited extent independent of the gear in making axial adjustments of the roll necessary in the operation of corrugating the same.

r is a worm held to rotate in bearings *u*, rigid with the flange *T* of the plunger, with its 55 spirals engaging the teeth of the gear. The worm is provided with a long stem or shaft, *s*, supported at its outer end by an arm, *c*⁸, extending out from the plunger, at the outer end of which stem is secured a ratchet-wheel, 60 *b*', and pawl-lever *k*', carrying a pawl, *a*', to act upon the teeth of the ratchet, the last-named parts being more clearly shown in the various figures of Sheet 2.

Horizontal pins *d*' and *d*², Sheets 2 and 3, are 65 held, by means hereinafter described, in positions to be encountered by the lever *k*' of the index as the latter reaches its uppermost and

lowermost positions by the vertical movements of the plunger above described. By means of these pins the lever is alternately 70 moved upward and downward, causing the pawl to turn the ratchet, and thus shift the roll for a new cut at each descent of the same.

The indexing of the roll, or the distance it is turned upon its axis at each advance movement of the pawl, is regulated for coarser or finer corrugations by forming a joint, *c*', in the pawl-lever, and providing an adjustable stop device for the latter. The stop shown is a threaded bolt, *g*', passing through a lug, *e*', 75 projecting from the pawl-lever in position to have its point encounter a rigid stud, *h*', of the flange of the plunger when the lever is carried downward by gravity, or by encountering the pin *d*², above mentioned. If the point 80 of the bolt touch the stud before the pin *d*² ceases its action upon the pawl-lever, the latter will, on account of its joint, yield to the pin, as shown, during which time the pawl will remain inactive, the action of the pin *d*² upon 85 the lever being effective only until the motion of the latter is stopped, as stated.

The bolt *g*' may be adjusted endwise in the lug *e*', so as to encounter the stud sooner or later in the movement of the lever, allowing the 90 point of the pawl to cover more or fewer teeth of the ratchet at each movement, the roll *F*' being indexed or turned upon its axis to a greater or less extent, according to the number of teeth passed over by the pawl. A nut, *n*', 95 threaded upon the bolt *g*' and turned tightly up against the faces of the lug *e*', serves to hold the bolt firmly in any position of adjustment given it. A flat spring, *i*', secured to the main 100 part of the pawl-lever and pressing against a projection, *l*', of the outer jointed end, *f*', of the same, tends to keep said part *f*' in the relative position shown in full lines in the figures, and when the part *f*' of the lever is bent downward by the pin *d*², as above described, it is done against the action of the 105 spring.

Instead of a single ratchet, a nest of differential ratchets may be employed, if found convenient, in indexing the rolls for corrugations 110 of different numbers or fineness, each having a pawl to operate it.

If after the roll is put in position for a cut it be carried straight upward between the cutters, the corrugations will be straight and 115 truly longitudinal, but by slowly turning the roll upon its axis while moving upward the corrugations will be given a spiral form.

The roll, with the index, plunger, and other parts, may be turned upon its axis independently of the indexing movement by the following means: *G*', Sheets 2 and 3, is a straight twist-bar or guide standing nearly vertical at the rear of the machine, having its lower end secured in a pivot-block, *H*', secured to the 120 flange *A* by means of a rigid bracket, *I*', which pivot-block is fitted to turn in a vertical plane upon a rigid stud or bolt, *K*', reaching out 125 horizontally from the bracket. At its upper 130

end the guide is provided with a head, L', held by a bolt, p', Sheet 6, to a rest or girt, N', secured to the posts, as shown, said bolt passing through a circular slot, r', in the rest and 5 entering the head. By means of the slot and pivot-block H' the guide, when the bolt p' is loosened, may be swung at its upper end in a vertical plane to occupy a vertical position, as indicated by dotted lines; or it 10 may be inclined more or less to the right of a vertical, as shown, the bolt p' serving to clamp it firmly against the rest in any position of adjustment. The plane of the axis of the guide is at all times parallel to the axial 15 line of the engine, a portion, v', at the middle of the rest for the same, being made straight to carry truly the upper end of the guide in its lateral movements. A part, O', held to slide along the twist-bar or guide, reaches out 20 from the flange of the plunger, and is formed to have a pivotal motion in a vertical plane. Now, it will be understood that if the guide be held in an inclined position the plunger, 25 worm-gear, roll, and other parts will be turned slowly upon their axes as they are carried upward, giving to the corrugations made on the roll a spiral form; and it will be plain that the degree of the twist or wind given the 30 corrugations will depend upon the obliquity of the guide, and that if the latter occupy a vertical position no wind or twist will be given said corrugations.

The part O' is permitted to turn as it moves upward or downward along the guide G' by 35 being secured to a simple sleeve, P', Fig. 6, Sheet 6, fitted to turn upon a stud, e', secured rigidly to the plunger.

Parallel arms b' and b'', Sheets 2 and 3, projecting, respectively, from the upper head of 40 the guide G' and the pivot-block, hold at their extreme ends a rod, f'', parallel with said guide, upon which are secured the pins d' and d'', for operating the pawl-lever k' of the indexer c'', above described. These pins are secured to 45 the rod f'' by means of set-screws, or otherwise, to be adjustable upward and downward thereon, so that the indexer may be timely operated for corrugating rolls of different lengths. The rod f'' may be round, square, or of other 50 form of cross-section, square being thought to be best with gibbs under the points of the set-screws.

As above stated, the shaft O is fitted to slide as with a journal-fit through the guide R of 55 the frame. A rack, g'', and pinion h'', Sheets 3 and 4, are provided for the shaft, by means of which to raise or lower the latter by hand, the pinion being secured to a horizontal shaft, R', provided with a hand-wheel, S', and resting in bearings k'' and l'' upon the lintel or frame. The rack is longitudinally concaved upon its rear surface, so as to fit the convexity of the shaft, being confined endwise between collars o' and o'', secured rigidly thereto. By this 60 manner of fitting the parts the shaft is permitted to turn upon its axis in the guide or bearing R independently of the rack, and to slide

with the rack vertically through the guide, a space, r', being formed in the lintel back of the pinion, in which to receive the rack. 70

As above stated, the lower end of the shaft is formed with a longitudinal concentric chamber, u', Sheet 1, for the purpose of receiving a stem of the roll, the shell or wall surrounding the chamber being divided into parts or 75 jaws d'' by longitudinal slits s.

For a short distance from the end the shaft O on its outer surface is tapered and formed with a screw-thread, t', upon the tapered part, to which is fitted an internally-threaded ring-nut, T', as shown in Fig. 13, the same being also internally tapered to fit the taper of the shaft. On account of this construction the jaws d'' will be contracted at their free ends by 80 turning the ring-nut upward upon the said shaft. The diameter of the cavity u' is just sufficient to receive a stem of the roll, and the nut T', when turned upward, causes the jaws to firmly pinch the stem. When the roll-carrying shaft O is thus firmly clamped upon the 85 stem of the roll, it moves up and down with the roll, and likewise turns with it during the 90 operation of corrugating the same.

The work of corrugating mill-rolls has to be 95 very accurately and carefully performed, on account of which each cutter needs to be held so that it may be finely and exactly adjusted to its work, and also held rigid and unyielding while cutting. Besides, during each descent

or retrograde movement of the roll, the cutters have to be drawn slightly back therefrom to prevent injury to both cutters and rolls. As 100 has been already stated, the cutters are secured to prismatic stocks C', Sheet 8, fitted in radial races p'', Sheet 4, formed in the annular tool-holder A'', which latter lies in a horizontal position upon the tool-frame L and is firmly bolted thereto. The roll moves up and down through the central opening of the tool-holder in a line at right angles to the plane of the latter and 105 concentric therewith, the grooving-tools all pointing radially toward the roll.

The tool-holder consists of an annular plate, B'', formed with overhanging sectoral blocks C'', of one piece with the ring, between which blocks the tools rest, and a ring, D'', firmly secured to the sectors by bolt f'', concentric with the plate B'', covers said tool-stocks or tools. Within the races p'' thus formed the tool-stocks move endwise to carry the cutters 110 to and from the work. Under the overhanging ends of the sectors C'', and outside of the ring B'', is fitted another ring, F'', formed with a slot, c'', under each race p''. This ring F'' is made slightly thinner than the ring B'', so that 115 when the latter is secured in place upon the tool-frame, as stated, the former will turn freely but snugly around upon its bearing upon the ring B'', and between the overhanging sectors and upper surface of the cross-head 120 or tool-frame L. The slots c'' are substantially circular, but not concentric with the ring, one end of each being purposely near the outer periphery and the other near the inner pe- 125 130

riphery of said ring. Each tool-stock is provided with a downward-projecting stud, a^2 , (more fully described hereinafter,) in position to enter the slot c^2 when the tool-stocks 5 are put to place in the races, said studs being each provided with a friction-bushing, e^2 , to reduce the friction between them and the ring as the latter is moved.

From the obliquity of the slots c^2 in the ring 10 it will be seen that if the latter be turned in the direction indicated by arrow z^2 the tools will be urged inward toward the roll, and if turned in the opposite direction they will be drawn away from the roll, the sides of the 15 slots acting as cams upon the pins or studs of the tool-stocks. By this means a slight turning of the ring F^2 one way or the other upon its bearings serves to move all the cutters equally and simultaneously toward or from 20 the work, as the case may be. The ring may be turned by means of a tangent-screw (shown in Fig. 38) or other device; but we prefer to move it by a toothed rack and other means, as follows: G^2 , Sheets 4 and 8, is a dovetail 25 slide, fitted with a gib, H^2 , in a groove, I^2 , formed horizontally and transversely in the cross-head L . At its ends the slide is formed with two short standards, i^2 , which form bearings for a horizontal screw-shaft, n^2 , the same 30 being provided with an overhanging hand-wheel, r^2 .

n^2 is a prismatic tangent-block bored longitudinally, and internally threaded to receive the screw-shaft, said block occupying the space 35 between the standards i^2 of the slide opposite the edge of the ring F^2 . Upon its vertical face, turned toward the ring, the tangent-block is provided with transverse gear-teeth s^2 , which engage similar teeth formed upon the periphery of the ring, as shown, from which it will 40 be seen that by turning the hand-wheel r^2 the slotted ring will be moved upon its bearing with the tool-holder and tool-frame, causing the cutters to approach or recede from the 45 roll, as the case may be.

The block u^2 is preferably formed with longitudinal depressions v^2 in its upper and lower surfaces, in which to receive guides a^3 and a^4 to steady its movements, said guide a^3 being a 50 bar secured to the standards i^2 of the slide, and the guide a^4 being a simple upward-projecting part of the slide. This furnishes a means by which the cutters may be moved or adjusted by hand; but it is also desirable to have them 55 moved automatically to and from the work, to correspond to other automatic operations of the engine.

To move the tools automatically, we employ a segment arm or rocker, g^3 , pivoted at c^3 60 to a part, P , of the tool-frame. (Shown on Sheets 4 and 5.) This rocker is formed with a pin, n^3 , projecting horizontally outward to a position to be encountered and carried upward by a projection, h^3 , from the plunger when 65 the latter is at its upper position. (Indicated by dotted lines.) The rocker is also formed with peripheral gear-teeth i^3 , which engage

the teeth of a mutilated pinion, k^3 , by which the latter is made to turn through a half-revolution at each movement of the rocker. The 70 pinion is bored out longitudinally, and formed with a screw-thread throughout its bore, half of the distance (from one end to the middle) the thread being right-hand and the other half a left-hand thread, each preferably of equal 75 lead.

Studs e^3 and o^3 , of equal diameter, are secured rigidly, respectively, to an arm, p^3 , rigid with the tool-frame L and one end of the slide G^3 , the axes of the studs being in the same 80 horizontal line. These studs are externally threaded—one with a right-hand thread and the other with a left-hand thread—to fit the threads of the pinion, which latter is screwed onto the studs, as shown. From this combination of parts it will be understood that by turning the pinion one way or the other the studs e^3 and o^3 will be caused to recede from or approach each other, as the case may be, causing the slide G^3 , with the toothed block 85 u^2 , to move longitudinally within its bearing in the tool-frame. A longitudinal movement of the slide in either direction will cause the slotted ring to turn in a corresponding direction and move the tools to or from the roll, 90 as above stated, which is effected automatically by the action of the plunger in moving the segment arm or rocker above mentioned. The parts are so arranged that when the plunger moves upward its action upon the rocker 95 draws the tools back from the roll, as indicated by dotted position in Fig. 19, Sheet 8, after the roll has passed above said cutters, to the position indicated by dotted lines on Sheet 5. The cutters remain thus withdrawn from the 100 work until the plunger descends to its lowest position, when it moves the rocker in the opposite direction, by means described further on, and again brings the tools in position to act upon the roll, when the latter is carried 105 upward by another ascent of the plunger. By this means the tools are withdrawn automatically out of the way of the roll during its descent, and presented to act upon the surface 110 of the roll when it moves upward.

By means of the hand-wheel r^2 the cutters may be moved as a unit toward or from the roll at will, as above stated, and when left at any position of adjustment relative to the roll 115 said cutters will be returned to that exact position at each forward movement thereof caused by the action of the rocker—that is to say, if the noses of the cutters are adjusted by the hand-wheel to just touch, for instance, the surface of the roll as the latter passes up through them, and they are then left to the action of the rocker, they will be brought by the latter to just touch the roll at each forward movement given them by the rocker. This is an 120 important feature of the invention, as will be 125 presently understood.

In order that the cutting-edges of the tools may be brought back to the roll each time with great precision, which is necessary after

being drawn back to clear the latter in its descent, the pinion k^3 (see Sheet 4) must cease turning at the same exact point each time, and with positive means. The leads of the 5 threaded studs e^3 and o^3 are such that a half-rotation of the pinion is sufficient to draw the cutters sufficiently far from the roll to safely clear the latter as it descends. We form the 10 pinion with teeth only a part of the way around, and to stop its turning with exactness each time it moves, particularly when the cutters are brought to the roll, we provide it with tangential bars or stops a^3 on sides diametrically opposite, and provide the rocker 15 with similar stops, d^3 , to meet the stops of the pinion, as shown. The outward-turned faces of the stops of the pinion are slightly concaved, and the peripheral faces of the stops of the rocker are made slightly convex to 20 meet the concavity of the pinion-stops, the outer faces or bearing-surfaces of the stops of the segment-arm being made to conform to the pitch-circles of the teeth thereof. The stops of the pinion and rocker are formed so 25 as to meet and lap upon each other harmoniously as said pinion and rocker turn together, the pinion ceasing to rotate the instant the stops fairly coincide throughout their length in any given case. A continued 30 motion of the rocker at either end of its throw, after the stops are brought thus together, would result in no further motion of the pinion, the stops merely sliding upon each other. This causes the motions of the pinion and of 35 the cutters to be that of precision and exactness, while the movements of the rocker may be more or less variable or indefinite from the indefinite motion of the plunger.

Besides the adjustment of the tools by the 40 hand-wheel and the automatic movement of the same by the rocker, it is desirable to give to each an independent adjustment, so that all may be brought to bear alike upon the surface of the roll. To effect this, we form vertical rectangular cavities ℓ^3 , Sheet 8, in the respective 45 tool-stocks, in which to receive the square heads t^3 of the studs a^3 , as shown. These heads fill the cavities laterally, fitting the side walls thereof; but space is left in front and in 50 rear of the heads to allow a longitudinal motion of each tool-stock independent of its stud. An externally-threaded sleeve, r^3 , of comparatively large diameter, is fitted to an internally-threaded horizontal opening through the 55 rear wall, s^3 , of the cavity ℓ^3 , having its flat inner end bearing against the rear face of the head of the stud, its outer end being squared to receive a wrench. This screw is bored longitudinally to receive another screw, w^3 , which 60 passes through the former, and the head of the stud being threaded in the latter. Outside of the sleeve-screw r^3 the screw u^3 is formed with a collar, v^3 , and a squared head, b^3 , upon which to receive a wrench. Now, by turning 65 the screw w^3 the head of the stud may be brought firmly against the point of the sleeve-

screw in any position of adjustment of the latter in the tool-stock, and when thus firmly held the tool-stock and stud a^3 become rigidly joined. From this manner of fastening the 70 respective studs and tool-stocks together it will be seen that either tool of the series may be at any time independently adjusted.

When this engine is used where there is a system of water-works, a pipe-connection may 75 be made therefrom with the cylinder, by means of which the plunger may be carried upward, as stated; but we prefer to make the machine complete within itself, and for that purpose add to it a system of force-pumps, K^2 , Sheets 5 and 80 8, with which to fill the cylinder, and a system of outlet-valves, L^2 , Sheets 1 and 7, with which to exhaust the same, supplying devices or means by which said pumps and exhaust-valves may be worked and controlled automatically. 85

d^4 , Sheet 8, is a shaft for driving the pumps, being provided at one end with a step-pulley, N^2 , and at the other with a pinion, c^4 , said shaft resting in standards f^4 , rising from the flange 90 A of the cylinder.

g^4 is a similar parallel shaft resting in the same standards and provided with a gear, e^4 , operating with the pinion c^4 , said shaft being further provided with eccentrics h^4 , for operating the pumps. A series of small pump-cylinders, K^2 , are secured at the under surface of the flange A below the eccentrics, and jointed rods i^4 extend from the eccentrics to the plungers of the pump-cylinders, by means of which 100 the latter are operated. A pipe, k^4 , connected with the series of pumps, leads to the interior of the cylinder, near the bottom thereof, below the plunger, by means of which apparatus the cylinder may be filled and the plunger forced 105 upward, for the purpose above set forth.

It is designed to have the shaft d^4 continually running, by means of a belt on the step-pulley, during the operation of the machine, the inconvenience of starting and stopping the 110 same, as the pumps need to be operated by shifting the driving-belt, being thus avoided. During the descent of the plunger the pumps need to be stopped and started again when the plunger is down, to effect which we provide the shaft d^4 with the sliding clutch l^4 , in 115 position to engage the teeth of the hub of the pinion, the latter being made to turn loosely upon the shaft. The clutch we operate automatically by the following means: 120

O^2 , Sheet 9, is a shifter for the clutch, forked at its upper end and fitted in a groove, n^4 , of the clutch, the shifter being formed to rest and slide upon the flange A of the cylinder, and held thereto by bolts r^4 , passing through slots 125 s^4 in the same. These slots are of sufficient length to allow the shifter to move either way far enough to throw the clutch out of and in gear, as stated. The shifter is formed with two opposing lateral projections, o^4 , which form bearings for a vertical sliding bolt, t^4 . At its lower end the sliding bolt is formed with a V-

head, u^4 , being provided also with a rigid collar, a^5 , and spiral spring b^5 between said collar and upper bearing, o^4 , the tendency of which spring being to hold the bolt down, with 5 its collar resting upon the lower bearing, as shown in Fig. 31. Beneath the V-head of the bolt is an opposing V-head, c^5 , which V-heads engage each other, as shown, the V-head c^5 being formed at the end of a bell-crank, d^5 , resting in a bearing, f^5 , of a standard, P^2 , secured to the flange A. The bell-crank is formed with a horizontal arm, g^5 , reaching out toward the flange T of the plunger, by means of which said bell-crank is rocked in its bearing 10 in the standard, as hereinafter more fully described, causing the V-head thereof to swing under the V-head of the bolt.

By observing Fig. 31 it will be understood that if the head c^5 of the bell-crank be urged 20 in the direction indicated by the arrow it will crowd the bolt t^4 upward against the action of the spring, but no motion of the clutch-shifter will result until the V-heads reach the relative positions shown in Fig. 32, in which the edges 25 are presented to each other. If, now, the motion of the lower head be slightly continued, the spring will quickly force the upper head, u^4 , down on the opposite side of the lower head to the position shown in Fig. 33, which 30 action of the spring will cause the clutch-shifter to slide along its bearing on the flange A, in the direction indicated by the arrow in said latter figure, carrying the clutch away from the pinion, as shown. A contrary motion 35 of the head c^5 will now cause the bolt to rise, as before, and throw the head of the latter over on the other side of the head c^5 , causing the clutch-shifter to lock the clutches together, as before. By this means the clutch 40 is thrown out or in, resulting in the stopping or starting of the pumps at intervals, while said clutch and shaft carrying it continually rotate. This sudden or quick movement 45 of the clutch in each direction by means of the spring and V-heads, while the bell-crank is moved slowly and indefinitely by the plunger, is desirable, and an important feature of our invention, as a slow movement of the clutch would be impracticable. At its outer 50 end the arm g^5 of the bell-crank is provided with a pin, e^5 , which stands in position to be encountered by the projection h^5 of the flange of the plunger, said projection having been above described as operating the rocker by 55 encountering the pin h^5 , Sheet 5. A vertical rod, h^5 , is attached by loose joints i^5 , respectively, to the rocker and the arm of the bell-crank, connecting the two, so that both 60 are moved simultaneously by the plunger, whether it encounters either the pin n^5 or the pin e^5 . When the projection h^5 , in the downward motion of the plunger, acts upon the lever g^5 , it turns the pinion h^5 and restores the cutters to the position in which they act upon the roll, as above described.

The outlet or discharge valves for the water in the hydraulic cylinder have to be opened

and closed with reference to the action of the pumps and plunger, being closed when the pumps are operating and while the plunger is 70 moving upward, and opened when the pumps are stopped, to allow the plunger to descend, which opening and closing of said valves is effected by means of the projection h^5 of the plunger-flange as it acts upon the rocker and 75 the arm of the clutch-shifting device, as described above.

n^5 , Sheets 2 and 7, is a lever fulcrumed to swing in a vertical plane upon a pin, o^5 , held by a hanger, h^5 , secured to a brace, G, of the cylinder, said lever passing through an opening, g^6 , in said brace. The right-hand end of this lever, as appearing in the figures, is made circular and provided with gear-teeth, which engage similar teeth of a vertical rack, l^5 , 85 fitted to slide in a guide, p^5 , secured to the flange A. The reciprocating rod h^5 , connecting the rocker and arm operating the clutch-shifter, passes downward from the arm through the flange A and connects with the rack l^5 , as 90 shown, by means of which rod the lever n^5 is caused to swing in a vertical plane upon its pivot. At the left-hand end, Fig. 11, the lever is expanded, made circular, and provided with a yielding spear-head, r^5 , fitted to slide longitudinally thereon. The spear-head or sliding block r^5 is slotted at s^5 , through which a headed stud, t^5 , passes, being secured rigidly in the lever, which forms a guide or stud along 95 which the spear-head may slide. The spear-head is formed with a projection, u^5 , opposite a similar projection, a^6 , of the lever n^5 , which together hold a rod b^6 , upon which is coiled a spiral spring, c^6 . The rod is made rigid in the projection u^5 , and fitted to slide through 100 the projection or bearing a^6 , on account of which, if the spear-head be urged backward, the spring will be compressed between the projections u^5 and a^6 , and tend to restore said spear-head to its normal place on the lever. 110

d^6 is a cross-head fitted to move vertically between slides f^6 , secured to a brace of the cylinder, in position relative to the spear-head to have the latter act upon a horizontal pin, i^6 , thereof. From the lower end of the cross-head a rod, h^6 , extends downward, and is connected with the valve-lever k^6 , Fig. 8. (See also Sheet 3.) The action of the spear-head is similar to that of the V-head of the spring-bolt of the clutch-shifting device 115 above described. The inclined edges of the spear-head that bear upon the pin i^6 are designed to be made hard, and the pin supplied with a hardened friction bushing or sleeve for the spear to bear against, for the purpose 120 of decreasing the friction and wear of the parts.

Regarding Fig. 10, if the rack l^5 be moved upward, the spear-head, from being urged against the pin i^6 , will move backward along 130 its bearing on the lever n^5 , against the action of the spring, until it reaches the position shown in Fig. 11. Up to this stage of the movement of the spear-head no motion of the

cross-head or valves will result; but as the point of the spear-head passes the pin the spring will quickly force it outward beneath the pin to the position shown in dotted lines, 5 causing the pin to glide upward along its upper surface, e^6 , raising the cross-head to the position shown in dotted lines. This action of the spear-head will cause the outflow-valves of the cylinder to be opened, as will be presently specified. A downward movement of the rack $\bar{r}^6$ causes an upward movement of the spear-head, which, as its point passes the pin, depresses the cross-head, serving to close the valves, the parts then occupying the positions shown in full lines. It will be observed that although n^5 is a lever of the first order, on account of the construction of the parts the rod h^6 will move in the same direction in which the rod h^5 moves.

20 The vertical movements of the cross-head are regulated as to distance by means of lateral projections u^8 thereof, Sheet 5, encountering rigid studs v^8 , reaching out from the respective slides f^6 . These studs may be located to stop the cross-head at any point desirable in its vertical movements, so as to regulate the distance which the tubes p^6 move in the sleeve-tubes $\bar{r}^6$ above mentioned, it being necessary for the former tubes to move only 25 sufficiently far downward to uncover the openings n^6 of the sleeve-tubes. The lower studs need to be located so the ends of the inner tubes will surely press against the packing-pads of the sleeve-tubes before the projections of the cross-head touch them, their use being mainly to prevent the ends of the tubes being forced too firmly against the pads, which might injure the same.

Any valves to let the water out of the cylinder for the purpose of allowing the plunger to descend that are sufficiently tight and prompt in action will serve the purpose of this machine; but we prefer the system of valves L^2 . (Shown more fully in Figs. 8 and 9 40 of Sheet 7.) These valves consist of tubes $\bar{r}^6$, passed vertically through the bottom plate of the cylinder, and fitted therein by means of screw-threads, said tubes being closed at their inner ends and formed with side openings, n^6 , 45 through which the water may flow outward from the cylinder, as indicated by the arrows.

p^6 are other tubes, open at both ends, telescoped within the outer or sleeve tube, $\bar{r}^6$, the former tubes being secured to a horizontal 50 plate or head, o^6 , below the cylinder, said tubes passing through the head and opening out below the same. A cup-shaped packing-box, r^6 , is fitted by means of screw-threads to each of the sleeve tubes $\bar{r}^6$, in position to press 55 rings of packing a^2 against the ends thereof, and around the inner tubes, to prevent water escaping between them. The upper inner ends of the tubes $\bar{r}^6$ are provided with flat packing-pads c^7 , against which the flat or straight ends 60 of the inner tubes are pressed to prevent the outflow of water. Any number of these sets of tubes desirable may be employed, four be-

ing shown in the figures. The plate or head o^6 , holding the inner tubes, rests upon the end of a lever, k^6 , at the other end of which lever 70 the rod h^6 , leading from the cross-head d^6 , is attached. The plate and lever are connected in a movable joint by a pin, b^8 , so that the lever may rock freely thereon in its vertical vibrations, the said lever being fulcrumed at 75 b^7 upon a pin projecting from a hanger, d^7 , secured to a brace of the cylinder.

From the above it will be understood that when the cross-head or valve-opening slide d^6 is forced downward by the spear-head the 80 valves of the cylinder will close and the out-flowing of the water therefrom stop, and when the cross-head is lifted the valves will be opened and the plunger permitted to descend. Thus the projection h^3 from the flange of the plunger, coming in contact alternately with the pin n^3 of the segment-arm and pin e^5 of the arm of the bell-crank, serves to adjust the cutters, stop and start the pumps, and open and close the valves.

To assist to hold the roll in exact line and concentric with the cutters during its upward movement, so the grooves shall be of uniform depth all around the same, rigid guides e^7 , Sheets 4 and 5, are secured to the under surface of the tool-frame L , with their inner ends bearing against said roll. These guides may be of any suitable form, having bearing-surfaces sufficiently broad in contact with the roll, and being made horizontally adjustable 100 upon the tool-frame by means of slots f^7 , or otherwise adapted to be used when rolls of different diameters are being corrugated. Three or more of these guides may be employed, they being distributed equally around 105 the circumference of the roll.

The parts P of the tool-frame are clamped firmly to the posts I by means of bolts g^7 , to enable said tool-frame to withstand the upward thrust of the roll as it is driven through the cutters by the plunger. To prevent the cross-head or tool-frame bending, from the strain brought against it by the upward-moving roll, we provide vertical brace-rods R^2 , Sheets 1 and 3, fitted within hubs h^7 of the lintel, which 110 may at any time be brought to bear upon the cap-ring D^2 , for the purpose of sustaining said cross-head against the strain. These brace-rods or supports are fitted to slide vertically within the hubs, set-screws i^7 serving to clamp 115 or hold them in position of vertical adjustment given them. At their lower ends they are bored out longitudinally, internally threaded, and provided with threaded bolts k^7 , having pointed heads l^7 , to bear upon the cap-ring 120 of the tool-holder. By means of these bolts, after the supports are brought down to place, a heavy pressure may be brought to bear upon 125 said cap-ring. Jam-nuts n^7 are provided for the bolts k^7 , by means of which the latter are 130 firmly held to place when they are adjusted to the cap-ring, as stated.

The upward movement of the plunger is communicated to the roll by means of thrust-

bolts o^7 , threaded vertically in the studs or 5 holders w , above mentioned, rising from the worm gear. These bolts are made with pointed heads p^7 , (Fig. 36, drawn to a larger scale,) 10 similar to the heads of the bolts k^7 of the supports R^2 , and provided with similar jam-nuts, r^7 , to hold them rigidly to place in different 15 positions of adjustment. The strain brought to bear upon these thrust-bolts is sometimes 20 very great, on account of which we prefer to provide them with caps t^7 , hollowed to receive the points, which caps serve to distribute the 25 pressure against the roll over a greater surface.

Referring to Fig. 18, Sheet 8, it will be seen 30 that the points or noses of the cutters are scalloped or formed with a series of equal projections, s^7 . These projections are accurately 35 made of the size the grooves are to be formed in the roll in cross-section—that is, they are 40 spaced as the said grooves are to be indexed, so as to uniformly and evenly corrugate the 45 convex surface of the roll. These projections or teeth of the cutters are not made in a straight line for each cutter, but formed so that a horizontal 50 line drawn tangent to each of them would be curved with its upper end, as appearing in the figure, nearer the roll. From this 55 it will be seen that the uppermost tooth or projection, u^7 , of the cutter will mark the roll 60 first as said cutter is brought toward the roll by means of the hand-wheel r^2 , as above described.

The teeth of a cutter are so arranged that 65 from u^7 to v^7 they will mark the roll in succession when urged toward it, each cutting the roll slightly deeper than the one following it. Further, when the cutters are urged against the roll by the hand-wheel, so that the tooth u^7 of each has by successive cuts formed a 70 groove of the desired depth, the teeth v^7 will just mark the surface of the roll and the intermediate teeth of each cutter form grooves varying in depths from the marks made by the teeth v^7 to the fully-formed grooves made 75 by the teeth u^7 . The tools are urged against the hardened surface of the roll by the attendant with caution and by degrees, several cuts being taken before the teeth u^7 have completed their respective grooves, the cutters being all 80 drawn back from the roll after each cut or upward movement of the roll by the rocker g^3 and combined parts, as above described. Now, if after the cutters are urged against the roll until the teeth u^7 of the several 85 cutters have each completed a groove, the indexer be caused to turn the roll on its axis in the direction indicated by the arrow to the amount of the distance between two adjacent grooves, and the roll be then passed again 90 through the cutters, each tooth u^7 will complete the incomplete grooves left by the tooth next to it, which latter tooth in turn will bring to a nearer state of completion the groove left by the next adjacent tooth, to be finished at 95 the next turn of the roll by the tooth u^7 , and so on through the series, each tooth bringing a groove one degree nearer completion than

the preceding tooth left it, the teeth v^7 at each advance turn of the roll marking out new grooves upon the smooth hard face of the roll. 70 Thus, on account of the number and nearness together of the cutters surrounding a roll the latter has to be indexed and passed through the cutters but comparatively few times to have its whole surface corrugated, each cutter 75 grooving its share or section of the surface. The indexer is brought into use or stopped by allowing the pawl to engage the teeth of the ratchet or turning it back therefrom.

The operation of our corrugating-engine is 80 substantially as follows: The roller to be corrugated is placed vertical in the engine, the clamp k and bushing-ring d being first placed upon one stem thereof, which stem, with the ring, is inserted in the cavity of the worm-gear, with the end of the roll resting upon the caps of the thrust-bolts o^7 . The shaft O , previously raised by means of the hand-wheel S' , is brought down to receive the upper end of the other stem of the roll, and clamped thereon by means of the nut T' , the clamp k being also tightened upon the lower stem of the roll and confined by the screws t . The pawl of the indexer is thrown back from the ratchet, so as not to turn the roll until required, and the 90 cutters brought to the roll by the hand-wheel and urged forward until the teeth u^7 cut grooves into the roll to the depth required. The pawl is then turned onto the ratchet and the engine 95 left to itself to complete the corrugating of the roll without further attention, a belt of common kind running upon the pulley N^2 furnishing the power required. Previous to bringing the cutters to bear upon the roll the twist-bar or guide G' is adjusted to give to 100 the corrugations the desired twist or spiral, and the pins d' and d^2 adjusted to be timely 105 acted upon by the indexing-lever k' as it is moved by the plunger, reference being had to the length of the roll to be corrugated. When 110 the roll moves upward past the cutters, the projection of the plunger turns the rocker and draws the cutters back, stops the pumps, and opens the escape-valves for the water. The 115 plunger descends as the water flows from beneath it until the roll passes the cutters, when the projection encounters the lever of the clutch-shifting device and returns the cutters for another cut, closes the outflow-valves, and starts the pumps, the roll being simultaneously 120 indexed for a new cut by the lever of the indexing device encountering the pin d' . This 125 operation is continued until each tooth u^7 arrives at the groove formed by the like tooth of the preceding cutter, when the corrugations are completed. The cutters being numerous and near together, quickly overtake each other's work as the roll turns within them, so that a roll is quickly corrugated, each cutter completing its share of the surface of the same. Time is also saved in corrugating a roll with 130 this machine, from the fact that the parts all work automatically, and no time is lost in operating any part by hand. The roll is guided

steadily upward and downward in its vertical movements by means of the plunger moving in the cylinder below it and the shaft O, moving in the guide R above it, and the plunger 5 constitutes a longitudinally and axially movable support or carrier for the roll.

What we claim as our invention is—

1. The cylinder-piece A³, formed with a cylinder, C, a horizontal flange at the upper 10 end of said cylinder, and braces G, distributed around said cylinder and extending up to said flange, in combination with supports I, rising from said flange and secured thereto, and lintel K, upheld by said supports, substantially 15 as set forth.

2. The adjustable guides e⁷, in combination with the tool-frame L, having a central opening, T², the cutters, and the roll-carrying shaft, said guides extending inward toward the roll 20 or other body to be operated on, and consisting of a horizontal part and a raised inner part, substantially as shown.

3. The combination of smooth stationary tubular guide R with shaft O, sliding longitudinally therein, vertical rack g², attached to 25 said shaft, and a pinion gearing with said rack, substantially as set forth.

4. The roll-carrying shaft O, in combination with a rack, g², and the shaft and pinion 30 for operating said rack, the latter moving longitudinally with said shaft, but allowing said shaft to turn while said rack remains stationary, substantially as set forth.

5. The tool-frame L, in combination with 35 brace-rods R², the blocks P, and supports I, and clamping devices for holding said rods, substantially as set forth.

6. The tool-frame L, the blocks P, and supports I, in combination with brace-rods R² 40 and clamping devices for holding said rods, the latter being provided with adjustable bearing-point l, substantially as described.

7. The thrust-bolts o⁷, arranged under the 45 lower end of the roll and receiving the pressure thereon, in combination with the holders to which they are attached, the reciprocating roll-operating shaft and plunger, and a support for said holders, substantially as set forth.

8. A pivoted guide arranged to occupy either 50 a vertical or inclined position, in combination with a plunger having an extended part engaging therewith, the frame, and tools, said plunger being capable of axial motion, according to the inclination of said guide.

9. The combination, in a power corrugating-engine, of the cylinder and plunger therefor, a worm-gear fitted to turn upon a bearing with the plunger, and a rotating worm, r, for the gear resting in bearings with the plunger, 55 for the purpose specified.

10. A longitudinally and axially movable support for the roll, gearing for turning said support as it rises, a pawl and ratchet for actuating said gearing, a lever moving with 60 said pawl, a stud or rod for engaging and actuating said lever, and an adjustable stop which limits the motion of the latter, said

lever having a yielding section to let it pass said rod or stud, substantially as set forth.

11. The tool-stock C' of a corrugating-engine, formed with a longitudinal groove, o, and transverse tongue i, in combination with the cutter f, formed with a longitudinal tongue, n, to fit the cavity o of the tool-stock, and the transverse groove e, to receive the tongue i 75 of the tool-stock, and bolts g, to hold the cutter and tool-stock together, substantially as described.

12. The tool-holder A² of a corrugating-engine, and the slotted ring F², fitted thereon, in 80 combination with tool-stocks C', provided with studs or pins a², which are adjustable independently of the said stocks, and operate with the slotted ring, substantially as specified.

13. The tool-stock C' of a corrugating-engine, formed with a cavity, l, in combination with a stud or pin, a², occupying said cavity, an externally-threaded sleeve, r², passing through a wall of the cavity, and a threaded bolt, u², resting in said sleeve and fitted with 90 a screw-thread to the head of the stud, substantially as and for the purpose specified.

14. A longitudinally and axially movable support for the roll or work, in combination with gearing for turning said support as it rises, 95 a rod or stud for engaging and actuating said gearing, and a regulator, substantially as set forth, which makes the action of said gearing constant.

15. The tool-frame of a corrugating-engine, formed with a slide-block fitted thereon, in combination with a screw-shaft, n², fitted thereto, and the toothed block u², fitted to the screw-shaft and formed to move longitudinally upon the slide-block, substantially as shown. 100

16. In combination with the tool-frame of a carrying-engine, formed with an arm, p³, provided with a rigid threaded stud, e³, a slide-block provided with a threaded stud, o³, and pinion k³, fitted to said studs, with a rocker-arm engaging with said pinion, for the purpose specified. 110

17. An arm moving with the roll, in combination with a ring oscillated thereby, connections between said arm and ring, and a series of cutters engaged by said ring and alternately advanced and withdrawn thereby, substantially as set forth. 115

18. In a corrugating-engine, the tool-holder A² and slotted ring F², fitted thereon, in combination with the tangent-block u², which engages with said ring, a tangential movement of said block causing the slotted ring to turn upon its bearing, substantially as described. 120

19. A tool-holder and series of tool-stocks arranged therein, in combination with an adjusting-ring for engaging with said stocks to adjust them all simultaneously, and screws bearing against the rear of said stocks, respectively, for adjusting any one of the tools 125 independently, substantially as set forth.

20. In a corrugating-engine, a pinion, k³, formed with stops a³, in combination with a toothed segment arm or rocker, g³, to turn the 130

pinion, provided with stop-bars d^8 , to meet the stops of the pinion, substantially as and for the purpose specified.

21. In combination with a series of cutters and a ring, whereby they are advanced and withdrawn, a rocking segment-arm which oscillates as the roll moves up and down, a pinion engaged by said segment to oscillate said ring, and connections between said pinion and ring, said pinion and segment engaging only during a part of the oscillation of the latter, in order that a variable motion of the roll may be transformed into an invariable motion of the cutters, substantially as described.

15 22. In a corrugating-machine, a longitudinally and axially movable support for the roll or work, in combination with the cutters, an inclined guide, and adjusting devices for regulating the inclination of said guide, for the purpose specified.

25 23. The rod f^2 , provided with laterally-projecting fingers d^2 , d^2 , fitted adjustably thereto, in combination with the pawl-lever k' of the indexing device, said rod being held in position to have said fingers encounter said lever k' , substantially as and for the purpose set forth.

30 24. In combination with the cylinder-piece of a corrugating-engine, a lever, n^5 , formed at one end with gear-teeth, and provided at the opposite end with a movable or sliding block, r^5 , fitted to said lever and actuated by a spring, a toothed rack, t^5 , to engage the teeth of the lever, and a reciprocating rod to operate the rack.

35 25. A lever, n^5 , of a corrugating-engine, formed with a projection, a^6 , and a stud or guide, t^6 , in combination with a movable head, r^5 , fitted to the lever, the said head being formed with a longitudinal slot, s^5 , and a projection, u^5 , a rod, b^6 , resting in said arm and projection, and a spring, c^6 , substantially as shown and described.

40 26. A tool-holder and a series of cutters, in combination with a ring which engages with and actuates all of said cutters, a sliding block, and intervening devices for moving said ring, and gearing, which reciprocates said block as the roll moves up and down, substantially as set forth.

45 27. In combination with a roll-carrying plunger and the cylinder and inlets for raising the same by the influx of liquid, the inlet-valves of said cylinder, and a spring-im-55 pelled spear-head or incline, which is moved by the rising of said plunger into position to suddenly open said valves, substantially as set forth.

50 28. The combination, in a corrugating-engine, of the cylinder with the lever n^5 , provided with a sliding head, the cross-head d^6 , with its guides f^7 and rod h^6 , and the lever k^6 , substantially as specified.

60 29. In combination with the roll-carrying plunger and an arm oscillated thereby, the outlet-valves which allow the escape of liquid below said plunger, a pin connected with said

valves to allow them to be opened and shut, a sliding spear-head or incline arranged to slide back as its lower side comes in contact with 70 said pin, a spring which forces said spear-head forward when its point passes said pin, and thereby causes the upper side of said spear-head to lift said pin and open said valves, a lever on which said spear-head is mounted, a 75 rocking arm oscillated by the rise and fall of said plunger, and connections between said arm and lever whereby the oscillation of said arm causes said spear-head to oscillate also, substantially as stated.

80 30. The cylinder C, having fixed tubes t^6 , extending from the interior to the exterior of said cylinder and provided with internal packing-pads, said tubes having their upper ends closed, and openings in their respective sides 85 just below said ends, in combination with tubes p^6 , which slide within said tubes t^6 , and a lever, k^6 , whereby the tubes p^6 are forced against said packing for closing said valves, substantially as shown and described.

90 31. The cylinder C, having fixed tubes t^6 , extending from the interior to the exterior thereof and provided with internal packing-pads, said tubes having their upper ends closed, and openings in their respective sides 95 just below said ends, in combination with tubes p^6 , which slide within said tubes t^6 , a lever, k^6 , whereby the former tubes are forced against said packing for closing said valves, and packing-boxes r^6 at the outer respective 100 ends, said tubes t^6 surrounding said respective tubes p^6 , substantially as described.

32. In combination with the cylinder of a corrugating-engine, the guides f^6 , provided with stop-pins v^7 , and the cross-head d^6 , provided with lugs u^7 , to encounter the stop-pins as said cross-head is moved up or down, substantially as described.

105 33. The shaft d^4 of a power corrugating-engine, provided with a loose clutch-pinion, c^4 , and sliding clutch t^4 , with the clutch-shifter O^4 , provided with a spring-bolt, t^4 , and spring b^5 , in combination with the bell-crank d^5 , operated by the plunger, substantially as described.

110 34. In combination with the roll-carrying plunger and a set of pumps for supplying liquid to the cylinder, a clutch on the driving-shaft of said pumps, an arm or lever operated by said plunger for unshipping said clutch, and a spring pressed V-head which is carried by said lever, said V-head operating suddenly to effect said unshipping when the point passes over the opposed part, substantially as set forth.

115 35. In combination with a roll-carrying plunger and a set of pumps which supply liquid to the cylinder, a shifting-clutch which controls the operation of said pumps, and a yielding arm or lever forming part of the 120 clutch-unshipping mechanism, said lever acting suddenly to effect said unshipping when the plunger reaches its highest point, substantially as described.

36. In a corrugating-engine, the arms g^5 and g^3 , connected by a rod, h^5 , in combination with the plunger for the cylinder provided with a projection, h^3 , to alternately encounter said arms, substantially as and for the purpose specified.

37. In combination with the cylinder of a corrugating-engine, the rotating pulley-shaft d^4 , resting in standards f^4 thereon, provided with a pinion, c^4 , the parallel shaft g^4 , provided with gear e^4 , eccentrics h^4 , and a series of pumps, with pipe connecting said pumps and cylinder, substantially as shown and described.

38. In combination with a longitudinally and axially movable support for the piece being corrugated, an adjustable inclined guide which engages with an extended part of said support to regulate the twist of the corrugations, and a girt or rest, N' , for the inclined

guide, having a curved slot which engages with the head formed on said guide, substantially as described.

39. In combination with the fluid cylinder of a corrugating-engine provided with tubes t^6 , communicating between the interior and exterior thereof, having their inner ends closed, formed with side openings, n^6 , and provided with packing-boxes r^4 at their respective outer ends, the tubes p^6 , telescoped within said respective packing-boxes, and tubes t^6 , to cover said openings n^6 , and packing-pads within said tubes t^6 , substantially as described and shown.
